Primary Examiner — Rachel A. Voorhies*Assistant Examiner* — Gary N Chamberlin(74) *Attorney, Agent, or Firm* — Birch, Stewart, Kolasch & Birch, LLP**CLAIM**

The ornamental design for a display screen with icon, as shown and described.

DESCRIPTION

FIG. 1 is a front view of a display screen with icon according to my new design; and,

FIG. 2 is another front view thereof which is an overturn of FIG. 1 by 180 degrees and shows a display screen with icon. The dot-dash line perimeter of each figure illustrates a display screen portion and forms no part of the claimed design. All other broken lines depict portions of the icon, and form no part of the claimed design.
